UNITED STATES PATENT OFFICE.

JOHN STRATTON, OF BOWDEN, AND ERNEST ALEXANDER CLAREMONT, OF HIGH LEGH,
ENGLAND.

EXTRUDING LEAD AND THE LIKE.

1,301,882.

Specification of Letters Patent. Patented Apr. 29, 1919.

Application filed April 18, 1918. Serial No. 229,407.

To all whom it may concern:

Be it known that we, JOHN STRATTON, a subject of the King of England, residing at Bowden, Cheshire, in England, and ERNEST ALEXANDER CLAREMONT, a subject of the King of England, residing at High Legh, Cheshire, in England, have invented certain new and useful Improvements in Extruding Lead and the like, of which the following is a specification.

This invention relates to the extruding of lead and the like in pipe or other required form.

In presses for extruding lead and the like heretofore in common use, the propelling force has been attained by subjecting lead in a molten condition to the pressure of a hydraulically-driven ram resulting of necessity in intermittent operation, the process being stopped every time the ram has completed its stroke. It has also been proposed to force molten lead as by means of feed rollers in a continuous process into or through an extruding machine, cooling it at or about the point of its passage where it is extruded through an annular aperture or die, so that it is finally extruded in a solid condition.

The object of the present invention is to construct an improved machine or series of machines or apparatus by which molten lead or the like is first introduced into the extruding machine, then more or less cooled in a chamber internally in the form of two parallel cylinders intersecting one another to form in cross section approximately the outline of the figure 8 before being acted on by extruding members in the form of inter-engaging rollers and then extruded in the desired solid form in a satisfactory and practical manner, so that an even continuous flow of the lead or like material can be extruded.

We have discovered by long continued experiments in connection with lead presses that it is impracticable to properly extrude lead in a plastic condition from a press by applying pressure, by means of a continuously acting pump or otherwise, to lead in a molten condition, the friction resulting in the endeavor to force the lead through the apparatus being so great that the operation fails.

The apparatus according to the present invention, however, receives the lead in a

molten condition, but does not apply pressure thereto in this condition, it not being until it has attained a plastic or partly cooled condition in its travel around the circumference of the sections of the 8-shaped chamber aforesaid that it receives pressure in the extrusion chamber and is forced through a die. Accordingly the main feature of the present invention is the said 8-shaped chamber, wherein the lead receives the pressure for the purpose specified.

In the accompanying drawings is shown an example of our invention adapted for the covering of an electric cable with a lead pipe or covering.

Figure 1 is a sectional elevation on the line A—B—C—D of Fig. 2.

Fig. 2 is a sectional plan on the line E—F of Fig. 1, the rollers hereinafter referred to being in perspective.

Fig. 3 is an elevation showing a general view of the complete machine.

Fig. 4 is a plan view of the same, and Fig. 5 is a vertical section on the line G—H of Fig. 2.

Similar letters refer to similar parts.

We construct the extruding machine as follows:—

a is the main body containing the chamber aforesaid internally in the form of two parallel cylinders intersecting one another to form in cross section approximately the outline of the figure 8. The said chamber is capable of being opened in a vertical plane through the center thereof to permit access of the interior: *a*¹ designates a hinge on which the two parts of the body *a* swing apart, *a*² designating hinged bolts pivoted at *a*³ and threaded at the opposite ends which pass through slots in projections *a*⁴ and are furnished with nuts *a*⁵ to clamp and secure the two parts of the body *a* together: *a*⁶ is a wall at right angles to the axes of the cylinders constituting the aforesaid chamber and dividing said chamber into two halves containing a passage *a*⁷.

In each of the cylinders, extending from one flat side or end to the other and occupying the whole of the chamber diametrically, is a roller *b* with parallel projecting teeth or longitudinal ribs *c* and intervening spaces *c*¹ so constructed that as the rollers rotate on their axes, the teeth of the one roller engage with the spaces of the other. In the construction illustrated the teeth are

shown as slightly helical or wormed, there being a pair of separately driven rollers in each half of the 8-shaped chamber formed by the dividing wall a^6 . The rollers are 5 provided with brass bushes b^1 around the shafts or axles b^2 , and preferably the axle of each of the rollers is integral therewith and projects at each end, and is supported and works in a bearing in the body of the 10 chamber. At one end the axle may pass through an aperture in the wall of the chamber and be connected with driving mechanism, but the rollers might be otherwise suitably supported and driven. If 15 only one of the rollers is to be driven, the axle of but one of said rollers passes through the wall of the chamber.

The chamber is provided with an extruding opening, and its sides in proximity 20 thereto are suitably shaped or inclined to form what may be termed a pressure chamber g . The said extruding opening is of the required shape and may have a core or not according to the nature of the material or 25 article to be dealt with. The said opening is preferably so placed that it is evenly bisected by a plane at right angles to the plane of and parallel to and equidistant from the axes of the rollers b . The chamber 30 is provided with a suitable number of inlets h to receive the molten lead or the like on the side of the chamber opposite the extrusion opening, the said inlets being preferably in the form of long slots extending 35 from end to end of the chamber and conducting the lead to said chamber from hoppers h^1 attached to the body a by threaded bolts h^2 .

For the purpose of forming a covering of 40 lead or the like on an electric cable or other elongated article when it is necessary to pass said cable or article through the press, the 8-shaped chamber is divided as aforesaid into two halves by the wall a^6 in which is 45 formed the passage a^7 communicating with the pressure chamber and through which the cable passes, the said passage being provided with a suitably shaped core and die. In the construction illustrated a core-box d 50 is provided which may be bolted to the body a through the flange d^1 , an extension of the dividing wall a^6 being formed in the core-box as at d^2 and this extension being cut away to gradually approach a circular projection, its external walls assisting to form 55 parts g^1 of the pressure chamber within the die box. Within said box d is also the die e held in place by means of the nut e^1 and co-operating with a core f in the passage a^7 60 within which is also an adjustable core holder or sleeve f^1 and an elongated nut f^2 for holding the core-holder in position.

The operation of the machine is as follows:—

The lead or the like is reduced to the

molten state in any suitable lead pot and by means of pipes or conduits with suitable valves to control the flow (not shown), it is conducted to the hoppers h^1 and fed thence into the 8-shaped chamber by the inlets h . 70 The lead from said inlets is received by the spaces c^1 between the teeth c and is carried around the cylindrical parts of the chamber in the direction of the arrows in Fig. 1 (being cooled to the plastic condition in its 75 progress around said periphery). The rotation of the rollers in the direction indicated causes the teeth to be separating toward the inlets h to the chamber, and engaging toward the extrusion opening. The teeth are 80 so shaped that when engaging they cause the lead between each successive pair of teeth to be displaced and deposited in the parts g of the pressure chamber. By the continued depositing of the lead as aforesaid, it is forced into the other parts g^1 of the pressure chamber and thence continuously through the extruding opening between the die e and core f without the necessity of stopping the process to form a pipe 90 or covering around the cable which is being passed through passage a^7 and the core.

It will thus be seen that although the lead is fed into the machine in a molten condition it cools and solidifies while being carried around the peripheries of the two halves of the 8-shaped chamber. The latter if desired can be furnished with a cold water jacket or other means well-known in the art 95 to assist the desired result.

For the purpose of securing a more perfect discharge of lead from between the teeth c of the rollers b we may momentarily hasten the drive of each of the rollers in advance of the other alternatively, or by 105 driving one directly and the other indirectly, alternatively control the impingement of each tooth on the engaging tooth in front or behind as may be found desirable.

Claims:

1. A machine for extruding lead or the like in the shape of a pipe or other desired form comprising in combination a chamber internally in the form of two parallel cylinders intersecting one another to form in 115 cross section approximately the outline of the figure 8 and wherein molten lead is partially cooled or solidified to a plastic condition, revoluble interengaging toothed rollers within said cylinders and approximately 120 filling the area thereof, means for introducing molten lead to said 8-shaped chamber, a pressure chamber communicating with said chamber and having an extrusion opening, and means for shaping the extruded lead as 125 desired in its passage through said extrusion opening.

2. A machine for extruding lead or the like in the shape of a pipe or other desired form, comprising in combination a chamber 130

- internally in the form of two parallel cylinders intersecting one another to form in cross section approximately the outline of the figure 8, and wherein molten lead is 5 partially cooled or solidified to a plastic condition, revoluble rollers having interengaging longitudinal projections or teeth within said cylinders and approximately filling the area thereof, means for introducing 10 molten lead to said chamber, a pressure chamber communicating with said chamber and having an extrusion opening, a coöperating core and die within said pressure chamber and means for conducting a cable 15 or other article through the core-die and extrusion opening for covering same with the extruded lead.
3. A machine for extruding lead or the like in the shape of a pipe or other desired 20 form, comprising in combination a chamber in the form of two parallel cylinders intersecting one another to form in cross section approximately the outline of the figure 8 and wherein molten lead is partially cooled or 25 solidified to a plastic condition, said chamber being divided into halves by a vertical wall at right angles to the axes of the cylinders to form a passage through same, separate pairs of revoluble rollers having interengaging longitudinal projections or 30 teeth within each half of the chamber on either side of said dividing wall and approximately filling the area of said cylinders, separate means for introducing molten 35 lead to each of said cylinders of the chamber, a pressure chamber communicating with said chamber and having an extrusion opening and a coöperating core and die within said chamber through which and the aforesaid passage a cable or other article may be conducted to receive a covering of lead issuing from said extrusion opening.
4. A machine for extruding lead or the like in the shape of a pipe or other desired form, comprising in combination a chamber 40 internally in the form of two parallel cylinders intersecting one another to form in cross section approximately the outline of the figure 8 and wherein molten lead is partially cooled or solidified to a plastic condition, revoluble interengaging toothed rollers within said cylinders and approximately filling the area thereof, means for introducing molten lead consisting of two elongated hopper receptacles having elongated passage- 45 ways leading therefrom to elongated openings in the chamber, one in each section thereof, a pressure chamber communicating with said chamber and having an extrusion opening, and means for shaping the extruded lead as desired in its passage through 50 said extrusion.
